UNITED STATES PATENT OFFICE.

JOSEPH BREWER, OF NEW YORK, N. Y.

CHECK.

Application filed August 4, 1921. Serial No. 489,861.

To all whom it may concern:

Be it known that I, JOSEPH BREWER, a citizen of the United States, and a resident of the city of New York, borough of the Bronx, in the county of Bronx and State of New York, have invented a new and Improved Check, of which the following is a description.

My invention relates to a negotiable paper such as a bank check and means to provide new and useful improvements therein.

It is well understood that considerable difficulty is experienced incident to the fact that it has been a common occurrence for checks to be "raised."

With this in mind any number of machines have been placed upon the market by means of which the face of the check might be marked in such a manner as to prevent the amount designated to be erased and a larger amount substituted.

For the most part these devices have objections in that they are too cumbersome for persons to carry with them and further in that they are relatively expensive.

With this in mind my present invention aims to provide a negotiable paper in the form of a check, by means of which it would be impossible to increase the denomination of the check without immediately rendering this alteration apparent.

A further object of my invention is the provision of a device of the character stated, which will permit of the conventional check protectors being entirely dispensed with aside from the fact that a negotiable paper embodying my improved construction will not cost any material amount more to manufacture than checks now placed upon the market.

With this and further objects in mind reference is had to the annexed specification taken in connection with the drawings which latter present a practical embodiment of the same, in which

Figure 1 is a face view of a check embodying my improved construction;

Figure 2 is a similar fragmentary view of a slightly different type of check;

Figure 3 is an enlarged transverse sectional view taken along the line 3-3 and in the direction of the arrows indicated in Figure 1.

Referring now more particularly to Figure 1 it will be seen that the reference numeral 5 indicates a check the body portion

of which is conventional in all respects and may bear any suitable data for being filled in in the usual manner as to the amount and signature, and it will also be noted in this view that three different safeguards are provided.

With respect to the first of these safeguards it will be noted that the reference numeral 6 indicates a series of strips attached to the body of the check 5, but capable of being severed therefrom. These checks are suitably identified and assuming that the check appears for an amount over one thousand it will be understood in the embodiment illustrated and as preferably constructed that all of the strips will be left in their proper positions, including a further strip (not shown) to the extreme right of the strip marked "Hundreds". This further strip, in the present case removed, is marked "Thousands". The reason for the removal here of such strip is because when the check is for less than one thousand dollars all those strips bearing characters designating amounts larger than hundreds will be severed therefrom. Obviously, after a strip is once severed, it will be impossible to attach same in such a manner as to escape vigilance of the paying teller.

The second form of safeguards utilized appears in the lower left-hand corner in the body of the check 5 and it will be seen that this safeguard consists of a number of tabs 7 entirely enclosed by the body of the check 50 and being capable of being removed therefrom for the same purpose as has been described in connection with the strips 6 in the preceding paragraph. Also, the digits from 1 to 0 are provided in the form of portions 8 of the check each properly identified and separable from the body of the check by virtue of the fact that they are entirely surrounded by a series of perforations rendering this operation comparatively easy.

Assuming that a check for \$10 is desired to be made all of the tabs 7 are removed with the exception of the one appearing on the lower left hand corner. Also the first and the last portion 8 in the top and middle rows, and the first only, in the bottom row are removed. Removal of the first and last portion 8 in any row will serve to indicate that none of the figures in that row are being used. Obviously this form may be omitted from a check and the form herein after described may be used.

However, the main safeguard is to be found in that tabs 9 hereinafter called the "literal" tabs, are provided in the body of the check which tabs indicate the character of the digits carried by the check. Also, supplemental tabs 10 arranged, hereinafter called the "numerical" tabs, and in a number of series, are provided adjacent the literal tabs 9 and it will be seen, reference being had to Figure 3, that these numerical tabs are constructed in such a manner as to afford a crescent-shaped space 11 at the top of each rather small numerical tab 10, which space enables the person filling in the check to readily remove these supplemental tabs.

Thus, as in the embodiment illustrated, the check is for \$987. First visualize the check intact as to the literal tabs 9, and with the tab 9 removed from the space 9^a marked "Thousands" and the tab 9 removed from the space 9^b marked "Hundreds". Now the theory of protection is that the unsevered literal tab overlying the left-hand digit-series of the tabs 10, limits the multiplier of the severed one of such tabs 10; that the unsevered literal tab overlying the middle digit-series of the tabs 10 has a corresponding function relative to the severed one of the last-mentioned digit-series; and that the same is true of the right-hand group of tabs 9 and 10. Therefore, as will be seen, the check being for \$987, as foreseen, the digit "9" is removed from the left-hand series of numerical tabs 10 and also the "Thousands" tab 9 (not shown) has been removed as indicated at 9^a. It will further be noted that the digit "8" is removed from the middle series of numerical tabs 10, and also the "hundreds" tab 9 (not shown) as indicated at 9^b. Finally, it will be noted that the digit "7" is moved from the right-hand series of numerical tabs 10, and also the "tens" tabs 9 shown in the present case partially severed.

In making out a check for say \$8,765, all the numerical tabs 10 would be left in place except the tab occupying the opening 9^a (as explained above, inscribed "Thousands"), the tab occupying the opening 9^b (as explained above, inscribed "Hundreds"), and the "Tens" tabs shown partially severed in Fig. 1. In this way, it is obvious that all but \$5 of the amount would be protected. Of course, if the length of the check permitted, a fourth set of digit-series tabs 10 could be provided, and then every single dollar would be covered. But such extra equipment is not recommended; as not even the most daring check-raiser would deem it worth while to tamper with a check for the sake of a gain of from \$1 to \$9, which is the most that would ever be left uncovered by the check such as that illustrated in Fig. 1, even where used for amounts as high as

\$9,999. Although an unauthorized person might succeed in carefully re-arranging one of the supplemental tabs or one of the main tabs, in such a manner that the deception would not be apparent, it is perfectly obvious that by virtue of the fact that more than one re-arrangement of the parts would have to be resorted to, a raising of a check is virtually impossible.

Referring to the form illustrated in Figure 2 it will be seen that the check in this view embodies only the essential elements of my invention, to wit, those embraced by the main and supplemental tabs 9 and 10 of the check illustrated in Fig. 1, this one safeguard in itself virtually precluding any possibility of a raising of the amount of the check. However, it will be noted in the form referred to that as will obviously be appreciated, I may readily provide merely one tab 9 for each of the series to indicate the class to which the digits of the latter belong.

Finally, again referring to the strips 6, it will be noted that the same are attached to the body 5 of the check in such a manner that a series of perforations or indentations is provided, which perforations are interrupted as at 6'. By this construction it will be obvious that an accidental detachment of one of the strips from the body of the check will be absolutely precluded and thus a person presenting the check for payment to a bank will be unable to put forth the excuse that the strips became accidentally torn from the body of the check, as it will be necessary to deliberately effect this operation.

Thus, it will be appreciated that all the objects set forth in the preamble of the specification are accomplished and it will be further understood that numerous modifications of the structure might readily be resorted to without departing from the scope of my claims, which are—

1. In a check of the character described, a check body carrying a plurality of permanent indicia divided into main and supplemental units, the supplemental unit indicating the digits and the main unit indicating the class to which said digits belong; the check having also a plurality of permanently cut-out portions with each said portion close to a particular indicium, each said portion being elongated and so disposed that a straight line joining the opposite ends of said portion faces its indicium sidewise.

2. In a check of the character described, a check body carrying a plurality of permanent indicia divided into main and supplemental units, the supplemental unit indicating the digits and the main unit indicating the class to which said digits belong; the check having also a plurality of permanently cut-out portions with each said

portion close to a particular indicium, each said portion being elongated and so disposed that a straight line joining the opposite ends of said portion faces its indicium 5 sidewise, the longitudinal side edge of each said portion nearest its indicium being curved and the convexity of said curve being directed away from said indicium.

3. In a check of the character described, a 10 check body carrying a plurality of permanent indicia divided into main and supplemental units, the supplemental unit indicating the digits and the main unit indicating the class to which said digits belong; 15 the check having also a plurality of permanently cut-out portions with each said portion close to a particular indicium, each said portion being elongated and so disposed that a straight line joining the opposite ends of 20 said portion faces its indicium sidewise, the longitudinal side edge of each said portion nearest its indicium being so shaped that a part of said edge intermediate the ends of said edge, and said indicium, are 25 located on opposite sides of said straight line.

4. In a check of the character described, a 20 check body carrying a plurality of permanent indicia divided into main and supplemental units, the supplemental unit indicating the digits and the main unit indicating the class to which said digits belong; 25 the check having also a plurality of permanently cut-out portions with each said portion close to a particular indicium, each said portion being elongated and so disposed that a straight line joining the opposite ends of 30 said portion faces its indicium sidewise, the longitudinal side edge of each said portion nearest its indicium being so shaped that a part of said edge intermediate the ends of said edge, and said indicium, are 35 located on opposite sides of said straight line.

5. In a check of the character described, a 40

check body carrying a plurality of permanent indicia divided into main and supplemental units, the supplemental unit indicating the digits and the main unit indicating the class to which said digits belong; 45 the check having also a plurality of permanently cut-out portions with each said portion close to a particular indicium, each said portion being elongated and so disposed that 50 a straight line joining the opposite ends of said portion faces its indicium sidewise, each said portion having opposite longitudinal edges which are arcuate.

6. In a check of the character described, a 55 check body carrying a plurality of permanent indicia, said check having also a plurality of permanently cut-out portions with each said portion close to a particular indicium and each said portion substantially 60 crescent shaped with the horns of the crescent directed toward its indicium, the check being slotted at opposite ends of the crescent, such slits constituting smooth prolongations 65 of the bounding arc of the crescent adjacent to the indicium.

7. In a check of the character described, the combination of a plurality of groups of individual digit indicia, each group including a separate indicium for each of a plurality of different digits, and a plurality of severable tabs located significantly adjacent to each of said groups of digit indicia, one tab of each plurality of tabs being inscribed with a digit-multiplier indicium and the 70 other tab of the plurality last-mentioned being inscribed with a dissimilar digit-multiplier indicium, but one tab of one plurality of tabs and one tab of another plurality of tabs being inscribed with the same digit-multiplier indicium. 75
